UNITED STATES PATENT OFFICE.

WILLIAM J. BOCK, OF LOOMIS, CALIFORNIA.

MAIL-BAG CATCHER.

No. 846,390.

Specification of Letters Patent.

Patented March 5, 1907.

Application filed August 16, 1906. Serial No. 330,840.

To all whom it may concern:

Be it known that I, WILLIAM J. BOCK, a citizen of the United States, residing at Loomis, in the county of Placer, State of California, have invented certain new and useful Improvements in Mail-Bag Catchers; and I do hereby declare the following to be a full, clear, and exact description of the invention, such as will enable others skilled in the art to which it appertains to make and use the same.

This invention relates to mail delivery and receiving mechanism for railway-trains, and has for its object to provide a mail-catcher which will include means for holding a bag in position to be caught by a passing train, a receptacle for bags from the train, and a device for delivering bags into the receptacle and for catching bags from the holding means.

Other objects and advantages will be apparent from the following description, and it is to be understood that I do not desire to be limited to the exact details of construction shown and described, for obvious modifications will occur to a person skilled in the art.

In the drawings forming a portion of this specification, and in which like numerals of reference indicate similar parts in the several views, Figure 1 is an elevational view of a bag holding and receiving mechanism. Fig. 2 is a top plan view showing a car passing the holding and receiving mechanism, the car being broken away to illustrate the delivery and catching arm. Fig. 3 is an enlarged detail view of the releasing-ring. Fig. 4 is a side elevation of the car, showing the mounting of the arm.

Referring now to the drawings, the present invention comprises a pair of uprights 5, to which there is attached a horizontal track 6, upon which there is mounted for movement longitudinally thereof a traveler 7, having wheels 8, which rest upon the track. A bracket 9 depends from the traveler between its ends and carries at its lower end an open-topped bag-receptacle 10, and steadyng members 11 are secured to the post and include spaced fingers 12, which receive therebetween the bracket 9 when the traveler is at the end of the track to prevent swinging of the receptacle through movement of the parts. From each end of the traveler there projects laterally a finger 13, these fingers extending in the same direction toward a track 14 adjacent to which the mechanism is located.

and a bag-receiving ring 14 is provided, as shown.

A pair of crossed levers 15 are pivoted upon the ring, extending outwardly and inwardly thereof, as shown, and the inner ends 60 of these levers have pivoted thereto the outer ends of two members 16, which are pivotally connected at their inner ends for movement into and out of alinement with each other. It will be seen that when these members are in 65 alinement with each other the levers 15 are held against movement. The upper ends of the levers 15 are pivoted to the lower ends of the shank 17 of a pair of pivotally-connected upwardly-directed jaws 18, arranged 70 to receive and hold either of two balls 13', carried one by each of the fingers 13, the arrangement being such that movement of the shanks 17 toward each other results in disengagement of the jaws from the balls, and a 75 spring 19, engaged between the shanks to hold them yieldably against such movement. As shown, a mail-bag is connected with the ring 14, and it will be seen that if the members 16 be moved upwardly at their 80 connected ends disengagement of the jaws from the ball 13' will result to detach the mail-bag from the holding mechanism or crane. It will be seen that the ring may be attached at either end of the traveler.

85 A catching and delivering arm 20 is revolvably engaged in a bracket 21, pivoted horizontally in a car 22, and it will be understood that each car is to be provided with one of these members. The arm extends outwardly of the car, having at its inner end a crank 22, by which it may be revolved and having a laterally-extending nose 23 at its outer end, this nose extending at right angles to the arm. A finger 24 is pivoted to the 90 outer ends of the arm for movement into and out of alinement therewith and is held normally in alinement with the arm by a spring 25, but is movable in either direction out of such alinement, this movement being in the 95 plane of the nose 23.

In use a bag to be delivered to the train is connected with the ring 14, as described, and the ring is connected to the traveler at the opposite side of the bracket 9 from the direction of approach of the train. A bag to be delivered at the station is engaged with the nose 23 by passing this nose through a ring connected with the bag, which may be a second ring 14, and the arm 20 is projected from 100 105 110

the car to bring the bag into position to pass over the receptacle 10, in which position the finger 24 is disposed to engage the bracket 9 for movement of the traveler with the train along the track 6, it being understood that the traveler is disposed at the end of the track in the direction of approach of the train. The arm 20 is also moved vertically to bring its nose 23 into position to pass through the ring 14 of the bag to be delivered to the train. When the movement of the train has brought the arm into position to lie with its bag above the receptacle 10, the finger 24 has engaged the bracket 9 to move the traveler with the train, and the arm 20 is quickly revolved to drop its bag from its finger 23 into the receptacle 10, after which it is quickly positioned to locate its nose 23 for passage through the ring 14, and when the traveler has come to the end of its movement the movement of the train will cause the finger 24 to move with respect to the arm 20, releasing the latter from the bracket and allowing the nose 23 to pass into the ring 14, when quick upward movement of the nose will engage the members 16, throwing them out of alignment and releasing the ring and bag from the traveler.

What is claimed is—

1. In a mail catching and delivering mechanism, the combination with a track, of a traveler movable upon the track, a bag-receptacle carried by the traveler, means for detachably connecting a bag with the traveler, and a member arranged for movement with respect to the traveler for delivery of a bag into the receptacle and for operation of the attaching means to release the latter, said member being arranged for movement of the traveler therewith.
2. A mail-bag holder comprising a fixed member, jaws engaging the fixed member and having shanks, said jaws being arranged for movement to release the member when the shanks are moved toward each other, a spring engaged between the shanks to hold them yieldably against movement to release the member, levers pivoted together to the shanks and pivoted in crossed relation, a bag-receiving member pivoted to the levers at their pivot-point, and members pivoted to the ends of the levers opposite to the shanks for movement into and out of position to hold said ends of the levers against movement toward each other.
3. In a mechanism of the class described, the combination with a track, of a traveler movable on the track, stops at the ends of the track, a bracket carried by the traveler, a receptacle carried by the bracket, steady-ing devices located in position to receive the bracket therebetween when the traveler is at the ends of the track to hold the latter against swinging movement, means for holding a bag

to the traveler, means for disengaging the holding means, and a movable member having a resilient finger engaging the bracket for movement of the traveler with the member, said finger being arranged for movement to permit of movement of the member independently of the bracket when the traveler has reached the limit of its movement, and a nose carried by the member for movement into position to operate the releasing means when the finger is disengaged from the bracket.

4. A receiving mechanism for mail-boxes comprising a track, a traveler movable on the track, a bracket depending from the traveler, a receptacle carried by the bracket, and steady-ing devices located at the ends of the track and arranged to receive the bracket to hold it with the traveler against swinging movement when the traveler is at the ends of the track.

5. In a mechanism of the class described, the combination with movable portions, of means for limiting the movement of said portions, an arm movable with respect to the movable portions, a finger pivoted to the arm and engaging the movable portions, a spring arranged to hold the finger yieldably against movement with respect to the arm, and in position for movement of said portions with the arm, said finger being arranged for movement against the action of the spring to permit of independent movement of the arm when the first-named movable portions have reached the limit of their movement, a bag-holder detachably connected with the movable portion, means for releasing the bag, and a nose carried by the arm for movement to actuate the releasing means after the finger is disengaged from the movable portions.

6. In a mechanism of the class described, the combination with a track, of a traveler movable on the track, a depending member carried by the bracket, means for limiting the movement of the traveler on the track, a ring detachably connected with the traveler and adapted for the attachment of a mail-bag thereto, an arm movable with respect to the traveler, a finger pivoted to the arm and engaging the opposite side of the depending member from the ring, said finger being movable toward and away from the member upon its pivot, a spring arranged to hold the finger yieldably against the depending member, and a nose carried by the arm in position for passage through the ring when the arm is moved over the depending member.

In testimony whereof I affix my signature in presence of two witnesses.
